UNITED STATES PATENT OFFICE.

ORSON MILLARD, OF FLINT, MICHIGAN, ASSIGNOR TO THE SUPREME DIVISION KNIGHTS OF THE LOYAL GUARD, OF SAME PLACE.

DESIGN FOR A BADGE.

SPECIFICATION forming part of Design No. 34,306, dated April 2, 1901.

Application filed March 5, 1901. Serial No. 49,664. Term of patent 14 years.

To all whom it may concern:

Be it known that I, ORSON MILLARD, a citizen of the United States, residing at Flint, in the county of Genesee and State of Michigan, have invented and produced a new and original Design for Badges, of which the following is a full, clear, and exact description.

In the accompanying drawings, forming part of this specification, I have shown my design in Figure 1 in front elevation and in Fig. 2 in longitudinal section.

The leading feature of my design, as shown in the drawings, consists of an erect eagle suspended from a bar, holding in each claw a flag, the staves crossed and the free ends of the flags furled across the staves. At the

intersection of the staves is a wreath. On the breast of the eagle is a star, the points interlaced in a flat ring. In front of all is a knight in full armor advancing, on his left arm a shield and in his right hand a spear.

Having described my invention, what I claim as new, and desire to secure by Letters Patent, is—

The design for a badge, substantially as shown and described.

In testimony whereof I have hereunto set my hand this 5th day of March, A. D. 1901.

ORSON MILLARD.
